CLAIM

The ornamental design for a housing for an automated blood pressure and other vital signs monitoring device, as shown and described.

DESCRIPTION

FIG. 1 is a perspective view of a housing for an automated blood pressure and other vital signs monitoring device, showing our new design, the broken line showing being for illustrative purposes only and forming no part of the claimed design;

FIG. 2 is a top plan view of the housing shown in FIG. 1;

FIG. 3 is a front elevational view of the housing shown in FIG. 1;

FIG. 4 is a left-side elevational view of the housing shown in FIG. 1;

FIG. 5 is a right-side elevational view of the housing shown in FIG. 1;

FIG. 6 is a back elevational view of the housing shown in FIG. 1; and,

FIG. 7 is a bottom plan view of the housing shown in FIG. 1.
